Primary Examiner — Jennifer Rivard*Assistant Examiner* — Melanie Pellegrini(74) *Attorney, Agent, or Firm* — Margaret Polson; Oppedahl Patent Law Firm LLC**CLAIM**

The ornamental design for braided bracelet with side buckle closure, as shown and described.

DESCRIPTION

FIG. 1 is a top plan view of my new design for a braided bracelet with side buckle closure.

FIG. 2 is a bottom plan view of FIG. 1.

FIG. 3 is a right side elevation view of FIG. 1.

FIG. 4 is a left side elevation view of FIG. 1.

FIG. 5 is a front elevation view of FIG. 1.

FIG. 6 is a back elevation view of FIG. 1; and,

FIG. 7 is a top perspective view of the braided bracelet closure in the closed configuration.

The dash-dot broken lines illustrate portions of the braided bracelet with buckle and form no part of the claimed design.

1 Claim, 2 Drawing Sheets(56)
